(57) **CLAIM**

The ornamental design for a baby car seat cover, as shown and described.

DESCRIPTION

FIG. 1 is a top, front and left side perspective view of a baby car seat cover, showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the baby car seat cover used on a baby car seat and its the front cover rolled inside;

FIG. 10 is a perspective view showing the baby car seat cover used on a baby car seat and its the front cover and its net rolled inside;

FIG. 11 is an enlarged view of portion 11 in FIG. 2; and, FIG. 12 is an enlarged view of portion 12 in FIG. 9.

The evenly broken lines in FIG. 9 and FIG. 10 illustrate environmental subject matter, which shows a baby car seat in actual use and forms no part of the claimed design. The unevenly dashed broken lines define the boundaries of enlarged views and form no part of the claimed design.
